Arthur R. Bentsen, Liverpool, N.Y., assignor to General
Electric Company, a corporation of New York

Application June 27, 1958, Serial No. 51,577

Term of patent 14 years

(Cl. D26—13)

Fig. 1.

Fig. 2.

Fig. 3.

Fig. 1 is a front elevational view of a wall plate for electrical switches and outlets or similar article, showing my new design;

Fig. 2 is a side elevational view, the opposite side being substantially a mirror image thereof; and

Fig. 3 is a perspective view thereof.

The broken line showings of fastening screws, switches and outlets are for illustrative purposes only.

I claim:

The ornamental design for a wall plate for electrical switches and outlets or similar article, substantially as shown and described.
